TENSIONING DEVICE

Gerhard P. Lessmann, Wilkinsburg, Pa., assignor
to Westinghouse Electric & Manufacturing
Company, East Pittsburgh, Pa., a corporation of
Pennsylvania

Application October 28, 1938, Serial No. 237,456

12 Claims. (Cl. 80—35)

My invention relates, generally, to tensioning devices, and, more particularly, to tensioning devices that may be employed to apply tension to a strip of material as it passes through a rolling mill.

It has become common practice in the operation of steel strip rolling mills to subject the strip to front and back tensions at each roll stand and to maintain tension on the strip as it is wound upon and unwound from the winding reel and unwinding reel, respectively. Until recently these tensions have been under the control of the mill operators, who adjusted the mill and reel motors to apply whatever torque they judged would produce the desired tension in the strip.

As the practice of subjecting steel strip to tension was developed, the strip tensions were increased and these tensions have become so high that at the present time the reduction of the strip due to the front and back tensions applied at each roll stand is a large proportion of the total reduction at the roll stand. With the strip tension playing such an important part in the rolling operation, and since the amount of reduction depends largely upon the amount of tension, it became necessary that the amount of tension applied to the strip be accurately controlled in order to produce a strip of uniform thickness.

A very successful device for subjecting the strip in a strip rolling mill to tension and automatically maintaining a predetermined amount of tension on the strip is shown and described in my copending application Serial No. 133,419, filed March 27, 1937, now Patent No. 2,189,609, issued February 6, 1940.

Many of the existing strip rolling mills whose operation it is desired to improve by the addition of automatic tensioning devices have their several roll stands and winding reel stands very closely spaced and have other apparatus mounted at and near the mill stands, leaving very little space for the tensioning devices and causing considerable crowding of machinery if indeed there is sufficient space for the tension devices. In building new strip rolling mills where plenty of space for the tensioning devices could be provided in laying out the mill, it is desirable that the mill be not spread out over too great a floor space and that a minimum of equipment be located at or near the pass line where it may obstruct the operator's access to the rolling equipment.

It is an object of my invention, therefore, to

provide an automatic strip tensioning device for a strip rolling mill which shall occupy a minimum of space at and near the pass line of the mill.

5 A more specific object of the invention is to provide a strip tensioning device for a strip rolling mill which may be readily adapted to and installed upon existing mills without interfering with the operation or accessibility of the operating parts of the mill.

10 A further object of my invention is to provide a strip tensioning device which may be readily adapted to and installed upon any of the several types of strip rolling mills and which shall function to subject the strip to and regulate front and back tensions at each roll stand and/or to provide automatically regulated winding reel and unwinding reel tensions.

15 Another object of my invention is to provide a strip tensioning device which shall be simple and efficient in operation and inexpensive to manufacture, install and maintain.

20 These and other objects and advantages of the invention will be apparent from the following detailed description taken in connection with the accompanying drawings, in which like reference characters denote similar elements of structure, and in which:

25 Figure 1 is a diagrammatic side elevation view, partly broken away, of a portion of a roll stand and strip reel of a strip rolling mill embodying the principal features of the invention;

30 Fig. 2 is a plan view of the apparatus of Fig. 1;

35 Figs. 3 and 4 are perspective views of portions of the strip tensioning device operating mechanisms and the mountings therefor shown in Figs. 1 and 2;

40 Fig. 5 is a diagrammatic representation of a single stand temper pass mill embodying the principal electrical control features of my invention;

45 Figs. 6 and 7 are a diagrammatic side elevation view and a simplified control diagram, respectively, of a two stand temper pass strip mill embodying the principal features of my invention; and,

50 Figs. 8 and 9 are a diagrammatic side elevation and a simplified control diagram, respectively, of a single stand reversible strip mill embodying the principal features of my invention.

55 In carrying out my invention, a tensioning device 10, best shown in Figs. 1, 2 and 4, is mounted upon the mill housing 12 and positioned to subject the strip 14 to a tension as it passes between

the rolls 16 and a strip puller 18. Another tensioning device 20 is mounted upon the mill housing 12 and positioned to subject the strip 14 to tension as it passes between the strip puller 18 and the strip reel 22.

The tensioning device 10 has its operating mechanism supported on a beam member 24 which in turn extends between and is supported by the upright members 26 and 28 of the mill housing 12. The tensioning device 20 has its operating mechanism supported on a beam member 30 which in turn is supported by bracket members 32, 34 and 35 secured to the uprights 26 and 28, respectively. The operating mechanisms of the tensioning devices 10 and 20 are supported sufficiently high above the pass line of the mill to preclude their occupying space in the area about the pass line where space is at a premium, and where considerable space is needed to insure freedom of access of the operator to the mill. Spaced linkage rods 36 and 38 extend downwardly from the operating mechanism of the tensioning device 10 and support a tensioning roll 40. Similarly, spaced linkage rods 42 and 44 extend downwardly from the operating mechanism of the tensioning device 20 to support a tensioning roll 46.

The simplified control diagram for a single stand mill is shown in Fig. 5. In this figure, there are shown a single set of rolls 16, a winding reel 22, an unwinding reel 22', and strip pullers 18 and 18' disposed between the rolls and the winding and unwinding reels, respectively.

The tensioning device 20 controls the tension exerted on the strip as it is wound on the winding reel 22 by means of a regulator which controls the field excitation of the winding reel drive motor. In a similar manner, the tensioning device 10 controls the front tension exerted on the strip by the strip puller 18 by field control of the puller drive motor. The unwinding reel 22' and the strip puller 18' are each connected to dynamic braking generators, and the tensioning devices 10' and 20' control the back tension and the reeling tension on the strip by field control of the generators associated with the strip puller 18' and the unwinding reel 22', respectively.

The system of Fig. 6 comprises two roll stands 48 and 50 with the strip tension between the stands controlled by a tensioning device 52. The winding reel tension, the unwinding reel tension, the front tension on the strip at the roll stand 48, and the back tension at the roll stand 50 are controlled by tensioning devices 20, 20', 10 and 10', respectively, in the manner described in the discussion of Fig. 5. These controls are shown in Fig. 7.

In Figs. 8 and 9, the tensioning devices 10 and 10' are shown employed to regulate the tension on the strip between the reels and the rolls of a reversible strip mill. The tensioning devices are connected to control the torque applied to the winding and unwinding reels by field control of the dynamo-electric machines associated with the reels.

Referring to Figs. 1 to 4 for a more detailed description of the preferred embodiment of my invention, the crossbeam 24 is made up of two sections 53 and 54. A plate 56 is secured to the end of the section 53 of the beam in any suitable manner, such as by welding, and the plate 56 is secured to one end of the beam section 54 in a similar manner. The plates 56 and 58 are

made to abut against a bracket member 60 and are secured thereto in any suitable manner.

The outwardly extending end of the beam section 54 may be secured to the mill housing member 26 in any suitable manner. The outwardly extending end of the beam member 52 is mounted upon a bracket 62, which is secured to the mill housing 28. The total length of the beam sections 52 and 54 is less than the distance 10 between the mill housings 26 and 28, and this total length is such as to permit the beam to be mounted on mill stands having a minimum spacing between the opposing mill housings. The bracket 62 extends from the housing 28 a distance such as to permit the mounting of the beam 24 on mill stands having different spacings between the opposing mill housings so that the tensioning device may be employed with mill stands having a considerable range of spacing between the opposing mill housings.

A bell crank 64 is secured to a shaft 66 which in turn is rotatably mounted on a bearing member 68, and which extends to, and is suitably supported upon, a corresponding bearing member (not shown) upon the opposite end of the beam 24 adjacent the mill housing 26. A roller 70 is rotatably mounted on one end of the bell crank 64, and this roller forms the contact member between the bell crank 64 and a pressure fluid operated actuator 72 therefor. The pressure fluid actuator 72 may be any suitable pressure fluid operated piston and cylinder arrangement, such as that shown diagrammatically in my above-referred-to Patent No. 2,189,609. A rod 74 connects the actuator 72 with plate members 76 and 78 which engage the roller 70 on opposite sides.

A bearing member in the form of a knife edge 80 is mounted upon the opposite end of the bell crank 64 to engage the link member 88, hereinbefore referred to, through a supportable bearing member upon the link member 88, as shown in Fig. 1. A suitable dashpot 82 may be provided to damp the motion of the bell crank 64 under the influence of the actuator 72.

A crank having a bearing member similar to the bearing member 80 is suitably mounted for rotation with the shaft 66 on the opposite end of the shaft and cooperates with the link member 88 shown in Fig. 2 to support the other end of the tension roller 46.

In Fig. 3 there is shown the corresponding elements of the tension device 20 for actuating the tension roller 46, and similar reference characters have been applied to similar elements in Fig. 3 and in Figs. 1, 2 and 4. The tension device 20 is also shown in elevation and in plan view in Figs. 1 and 2. In Fig. 2, it may be seen that the shaft 66' is rotatably mounted on a suitable bearing support 84 on the opposite end of the beam 30 from the supporting bearing 68', and that an arm 86 is secured to the shaft 66' and cooperates with the link 44 as the link 42 is actuated by the bell crank 64'. A dashpot 82' is provided for damping the action of the actuator 72'. The tension roll 46 is suitably guided by guide members 86 secured to the mill housings 26 and 28, and the tension roll 46 is suitably guided by similar guide members 88 suitably mounted on a supporting block 80.

The puller 18 comprises roll members 92 and 94 rotatably mounted upon supporting brackets 96 and 98, which in turn are suitably supported upon the mill housings 26 and 28, respectively.

The roll 94 is rotated through its shaft 100 by a suitable dynamo-electric machine 102 shown in Fig. 5. The roll 92 may be an idling roll or may be driven by the machine 102 also by suitable gearing connecting the rolls 92 and 94.

Referring now to Fig. 5 for a description of the controls for a single stand mill embodying the elements of structure shown in Figs. 1 through 4, the reel 22 is connected by means of the shaft 104 to a suitable dynamo-electric machine 106. An idling roller 108 is suitably mounted between the puller 18 and the reel 22, so that the strip 14 may always be held in a predetermined relation with the tension roll 46. Tensioning devices 10' and 20' similar to tensioning devices 10 and 20 are situated on the other side of the roll stand 16 and actuate tensioning rolls 40' and 46', respectively. A puller 18' operably connected with a dynamo-electric machine 106' is mounted in a position corresponding to the position of the puller 18 on the other side of the mill stand. A reel 22' operably connected with a dynamo-electric machine 106' is provided, and an idling or guide roll 108' is suitably mounted in a position similar to that of the guide roll 108. The machines 102, 102', 106 and 106' and the motor driving the reducing rolls are all connected by suitable controllers to a suitable source of power indicated by the conductors marked plus (+) and minus (-). The field winding of the machine 106 is suitably connected to a regulator, as indicated in Fig. 5, to be controlled in accordance with the degree of deflection of the strip 14 by the tensioning device 20 in a manner described in detail in my above-named patent. In a like manner, the motor 102 is controlled by the regulator actuated by the tensioning device 10, and the motors 102' and 106' are controlled by the regulators connected to be actuated by the tensioning devices 10' and 20', respectively.

In the operation of the mill shown in Fig. 5, assuming that the reel 22 is acting as a winding reel and that the reel 22' is acting as the unwinding reel for the strip 14, and the rolls of the mill are being driven in a direction indicated by the arrows, then the machines 102 and 106 will be acting as motors, and the machines 102' and 106' will be acting as generators to provide regenerative braking for the reel 22' and the puller 18'. As the strip passes from the reel 22', the tension on the strip as it leaves the reel will be regulated by the tensioning device 20' through the regulator actuated by the tensioning device 20' and acting upon the field winding of the dynamo-electric machine 106'. At the same time, the back tension on the strip 14 at the roll stand will be maintained at a constant desired amount by the puller 18' through the control of the dynamo-electric machine 102' acting as a generator by the regulator operated by the tensioning device 10'. Front tension on the strip 14 as it leaves the rolls of the roll stand 16 will be provided by the puller 18, and this tension will be maintained at the substantially constant desired amount by means of the field control of the dynamo-electric machine 102 acting as a motor through the regulator operatively connected to the tensioning device 10. In a similar manner, the tensioning device 20 will serve to regulate the field current of the dynamo-electric machine 106 acting as a motor so as to provide the desired tension on the strip 14 as it is wound by reel 22.

The two stand temper pass mill of Figs. 6 and

7 has tensioning equipment similar to that described in connection with Figs. 1 through 5. In this system, the tensioning devices 10 and 20 and the puller 18 are mounted on one side of one roll stand 48, and corresponding tension devices 10' and 20' and puller 18' are mounted on the opposite side of the roll stand 50. Front and back tensions are maintained on the strip 14 by a tensioning device 52, which is similar to the tensioning devices 10 and 20, and employs the principles described in detail in my above-mentioned patent. The tensioning device 52 comprises a shaft 66' with one of its ends pivotally mounted on a suitable bearing 68' which in turn is mounted on a crossbeam 30, these elements having similar reference characters as in Figs. 1 through 4. The actuator 72' for the tensioning device 52 is mounted upon a plate member 109 which may be suitably mounted upon the outside of the mill housing of the roll stand 50. The actuator 72' operates through a roller 70' to actuate a crank 110 which is suitably secured to the shaft 66'. A tensioning roller 112 is suitably mounted upon crank member 114 and a similar crank member cooperating with the other end of the tension roll 112, both of the crank members being secured for rotation with the shaft 66'. The tensioning device 52 controls the field current of the driving motor for the rolls of the roll stand 48, as indicated in Fig. 7, in a manner similar to that described in connection with the control diagram of Fig. 5.

In the operation of the system of Fig. 7, assuming that the strip 14 is passing through the mill from reel 22' to reel 22, the tensioning devices 20' and 10' will operate through the dynamo-electric machines 106' and 102', respectively, to maintain reeling tension and back tension on the strip 14, as described in connection with the system of Fig. 5. Front tension at the roll stand 50 and back tension at the roll stand 48 will be controlled by the tensioning device 52 which will act through its associated regulator upon the driving motor for the rolls of the roll stand 48 as indicated. The tensioning devices 10 and 20 and the puller 18 will cooperate as described in the discussion of the system of Fig. 5 to maintain a predetermined front tension upon the strip 14 at the roll stand 48 and a predetermined rolling tension on the strip at the reel 22.

In Figs. 8 and 9 are shown the adaptation of the tensioning device 10 to a reversible mill wherein the tensioning device 10 and a similar tensioning device 10' are employed to provide 55 reeling and unreeling tensions on the strip 14 and corresponding front and back tensions on the strip as it passes between the rolls of roll stand 116. The tension devices 10 and 10' are mounted upon the mill housings in the manner described in detail in connection with Figs. 1, 2 and 4, and cooperate in the manner indicated in Fig. 1 with the dynamo-electric machines 106 and 106' through the regulators associated with the tensioning devices to so control the power supplied 60 to the reels by the dynamo-electric machines 106 and 106' as to maintain the desired tension upon the strip 14.

In connection with this control system, it is to be understood that the reels 22 and 22' may act 70 as either winding or unwinding reels as the mill is reversed and the strip is run through the mill in opposite directions, and that any suitable control device may be provided in a manner common in the art to operate the dynamo-electric machines 106 and 106' either as motors or gen-

erators depending upon the direction of travel of the strip through the mill, and, therefore, upon whether or not the strip is to be subjected to a pull or a drag by the reels 22 and 22'.

It will be noted that in each of these types of mills to which the tensioning devices 10 and 20 are applied, the instrumentalities already existing on the mill, such as the reels 22 and 22' and the pullers 18 and 18' and the guide rolls 118 and 118', are so situated as to leave little room for the tensioning devices. The novel construction of the tensioning devices 10 and 20, whereby the operating members of the devices may be mounted well above the pass line of the mills where they will not obstruct movements of the mill operator, permits the installation of tensioning devices upon already existing strip rolling mills which have such instrumentalities as the pullers and reels closely spaced, without undue crowding of the equipment at the pass line. It is particularly to be noted that only the tensioning rolls and the two supporting links for each of the rolls extend into the pass line area, and that these are of such dimensions as to require very little space, thus leaving the pass line area practically unobstructed.

It is to be understood that any of the systems discussed hereinbefore may be operated as reversible mills by suitable control of the dynamo-electric machines connected with the reels, the mill rolls, and the pullers to operate them as either motors or generators as the direction of pass of the strip through the mill requires.

It will be seen that I have provided an automatic strip tensioning system for strip rolling mills which may be readily adapted to, and installed upon, any of the several types of strip rolling mills which shall function to subject the strip to and regulate front and back tensions at each roll stand, and to provide automatically regulated winding and unwinding reel tensions which shall occupy a minimum of space at and near the pass line of the mill, and, therefore, not interfere with the operation and accessibility of the operating parts of the mill, and which shall be simple and efficient in operation and inexpensive to manufacture, install and maintain.

In compliance with the requirements of the patent statutes, I have shown and described herein the preferred embodiments of my invention. It is to be understood, however, that the invention is not limited to the precise constructions shown and described, but is capable of modification by one skilled in the art, the embodiments herein shown being merely illustrative of the principles of my invention.

I claim as my invention:

1. In a tensioning device for a strip rolling mill, a tensioning roller disposed to bear against the strip as it passes through the mill to deflect the strip from its normal pass line and thus subject the strip to tension, an operating mechanism for causing said roller to bear against the strip, means mounting said operating mechanism on the mill housing above and substantially spaced from the strip, and link means operatively connecting said operating mechanism with said tensioning roller.

2. In a tensioning device for a strip rolling mill, a tensioning roller disposed to bear against the strip as it passes through the mill to deflect the strip from its normal pass line and thus subject the strip to tension, an operating mechanism for causing said roller to bear against the strip, a cross-member extending between and mounted

upon the housings of the mill above and substantially spaced from the strip as it passes through the mill, means mounting said operating mechanism upon said cross-member above and substantially spaced from the strip, and link means operatively connecting said operating mechanism with said tensioning roller.

3. In a tensioning device for a strip rolling mill, a tensioning roller disposed to bear against the strip as it passes through the mill to deflect the strip from its normal pass line and thus subject the strip to tension, a cross-member extending between and mounted upon the housings of the mill above and substantially spaced from the strip as it passes through the mill, an operating mechanism for causing said roller to bear against the strip comprising a shaft extending substantially parallel to said cross-member, means pivotally mounting said shaft for rotation about its axis on said cross-member, crank means secured to said shaft for rotation therewith, link means operatively connecting said crank means with said tensioning roller, and means for actuating said shaft.

4. In a tensioning device for a strip rolling mill, a tensioning roller disposed to bear against the strip as it passes through the mill to deflect the strip from its normal pass line and thus subject the strip to tension, crank means pivotally mounted on the housings of the mill above and substantially spaced from the strip, link means operatively connecting said crank means with said tensioning roller, and means for causing pivotal movement of said crank means to thereby cause said tensioning roller to bear against the strip.

5. In a tensioning device for a strip rolling mill, bracket means mounted upon the adjacent mill housings above and substantially spaced from the normal strip pass line, a cross-member extending between and mounted upon said bracket means, a shaft member, means pivotally mounting said shaft member parallel to and upon said cross-member, a bell crank secured to said shaft whereby the shaft serves as a pivot for the bell crank, a force applying means, means mounting said force applying means on one of the mill housings in operative relation with one arm of said bell crank, a lever mounted on the shaft for rotation therewith, a tensioning roller disposed to bear against the strip as it passes through the mill to deflect the strip from its normal pass line and thus subject the strip to tension, and link means operatively connecting said tensioning roller with said lever and said bell crank.

6. In a tensioning device for a strip rolling mill, bracket means mounted upon the adjacent mill housings above and substantially spaced from the normal strip pass line, a cross-member extending between and mounted upon said bracket means, a shaft member, means pivotally mounting said shaft member parallel to and upon said cross-member, a bell crank secured to said shaft whereby the shaft serves as a pivot for the bell crank, a force applying means, means mounting said force applying means on said cross-member in operative relation with one arm of said bell crank, a lever mounted on the shaft for rotation therewith, a tensioning roller disposed to bear against the strip as it passes through the mill to deflect the strip from its normal pass line and thus subject the strip to tension, and link means operatively connecting said tensioning roller with said lever and said bell crank.

7. In a strip tensioning device for a strip roll-

ing mill, a tensioning roller disposed to bear against and transmit a transverse force to the strip as it passes through the mill and thus subject the strip to tension, an operating mechanism disposed above and substantially spaced from the normal pass line of the strip and operatively connected with said tensioning roller to cause the roller to bear against the strip, and mounting means for said operating mechanism comprising a bracket member, a beam member secured to and extending outwardly from each of the opposite sides of the bracket member, and means mounting the outwardly extending ends of said beam members on the housings of the mill.

8. In a strip tensioning device for a strip rolling mill, a tensioning roller disposed to bear against and subject the strip to a transverse force as it passes through the mill and thus subject the strip to tension, an operating mechanism disposed above and substantially spaced from the normal pass line of the strip and operatively connected with said tensioning roller to cause the roller to bear against the strip, and mounting means for said operating mechanism comprising a bracket extending from each of the opposing sides of the mill housings toward the opposite mill housing, a beam member extending between said brackets, and means for adjustably securing said beam member to said brackets, the length of said beam member and the degree of the extent of the brackets from their respective mill housings toward the other mill housings being such as to enable said operating mechanism mounting means to be applied to roll stands of different spacings between mill housings.

9. In a strip tensioning system for a single stand reversible strip rolling mill, in combination, a strip reel disposed on each side of the mill, a dynamo-electric machine mechanically connected in operative relation with each of said reels, a strip puller disposed between the mill and each of the reels to thereby provide both front and back rolling tension regardless of the direction of pass, a dynamo-electric machine mechanically connected in operative relation with each of said reels, a first pair of strip tensioning devices one disposed to act on the strip between each of said strip pullers and the mill rolls, control means whereby each of said first tensioning devices controls the dynamo-electric machine associated with its adjacent strip puller to maintain substantially constant front and back tensions on the strip at the reducing rolls of the mill, a second pair of strip tensioning devices one disposed to act on the strip between each of said strip pullers and its adjacent reel, control means whereby each of said second tensioning devices controls the dynamo-electric machine associated with its adjacent reel to maintain substantially constant winding and unwinding tensions on the strip.

10. In a strip tensioning system for a tandem reversible strip rolling mill, a strip reel disposed beyond each of the end stands of the mill, a dynamo-electric machine mechanically connected in operative relation with each of said reels, a strip puller disposed between each of the reels and its adjacent roll stand to thereby provide both front and back rolling tension regardless of the direction of pass, a dynamo-electric machine mechanically connected in operative relation with each of said strip pullers, a first pair of strip tensioning devices one disposed to act on the strip between each of said strip pullers and its adjacent reel, control means whereby each of said

first strip tensioning devices controls the dynamo-electric machine associated with its adjacent reel to maintain substantially constant winding and unwinding tensions on the strip, a second pair of strip tensioning devices one disposed to act upon the strip between each of said strip pullers and the rolls of its adjacent roll stand, control means whereby each of said second strip tensioning devices controls the dynamo-electric machine associated with its adjacent strip puller to maintain the desired back and front tensions on the strip at the rolls of the first and last roll stands respectively, a strip tensioning device disposed to act on the strip between each adjacent pair of roll stands of the mill, and control means whereby each of said last named tensioning devices controls the driving motor for an adjacent roll stand to maintain the desired tension on the strip between each adjacent pair of roll stands.

11. In a tension control system for a strip rolling mill, in combination, a strip reel adjacent the mill, a strip puller disposed to act on the strip between the reel and the mill rolls, first and second tensioning devices, said tensioning devices comprising a tensioning roller disposed to bear against the strip to deflect the strip from its normal pass line and thus subject the strip to tension, an operating mechanism for causing said roller to bear against the strip disposed above and substantially spaced from the strip and link means operatively connecting said operating mechanism with said tensioning roller; the tensioning roller of said first tensioning device being disposed to bear upon the strip between said reel and said puller, bracket means extending outwardly from the sides of the mill housings toward said reel above and substantially spaced from the strip, and means mounting said operating mechanism for said first tensioning device upon said bracket; the tensioning roller of said second tensioning device being disposed to bear upon the strip between said puller and the mill rolls, inwardly extending bracket means mounted on opposing sides of the mill housing above and substantially spaced from the strip, and means mounting said operating mechanism on said inwardly extending bracket means.

12. In a tension control system for a strip rolling mill, in combination, a strip reel adjacent the mill, a strip puller disposed to act on the strip between the reel and the mill rolls, first and second tensioning devices, said tensioning devices comprising a tensioning roller disposed to bear against the strip to deflect the strip from its normal pass line and thus subject the strip to tension, an operating mechanism for causing said roller to bear against the strip disposed above and substantially spaced from the strip and link means operatively connecting said operating mechanism with said tensioning roller; the tensioning roller of said first tensioning device being disposed to bear upon the strip between said reel and said puller, bracket means extending outwardly from the sides of the mill housings toward said reel above and substantially spaced from the strip, and means mounting said operating mechanism for said first tensioning device upon said bracket; the tensioning roller of said second tensioning device being disposed to bear upon the strip between said puller and the mill rolls, inwardly extending bracket means mounted on opposing sides of the mill housing above and substantially spaced from the strip, and means mounting said operating mechanism on said inwardly extending bracket means, a first dynamo-

electric machine operatively connected with said reel, control means whereby said first tensioning device controls the operation of said first dynamo-electric machine thereby controlling the tension to which the strip is subjected between said reel and said puller, a second dynamo-electric machine operatively connected with said puller,

and control means whereby said second tensioning device controls the operation of said second dynamo-electric machine thereby controlling the tension to which the strip is subjected between 5 said puller and the mill rolls.

GERHARD P. LESSMANN.
